UNITED STATES PATENT OFFICE.

JOHN G. DORWARD, OF SAN FRANCISCO, CALIFORNIA.

COMBINATION PUMP-ROD GUIDE, COUPLING, AND VALVE CAGE.

Application filed March 9, 1922. Serial No. 542,345.

To all whom it may concern:

Be it known that I, JOHN G. DORWARD, a citizen of the United States, residing at the city and county of San Francisco and State 5 of California, have invented new and useful Improvements in Combination Pump-Rod Guides, Couplings, and Valve Cages, of which the following is a specification.

This invention relates to a pump, and 10 especially to a combination pump rod guide, coupling and valve cage for deep well pumps of the reciprocating plunger type.

Deep well pumps are as a rule not only submerged, but in practically every case positioned a considerable distance below the 15 surface of the well; in some instance several hundred feet. In view thereof it can readily be appreciated that accessibility under the best of conditions presents a difficult problem, hence requiring the best of workmanship and material when the working parts, such as valves, plungers, guides, etc., are considered, and further a structure which is simple, substantial and efficient in operation.

25 A great variety of valves is employed in pumps of this character, but practically all are objectionable either from a point of accessibility or otherwise. In many cases the valves do not seat or wear properly and 30 sometimes they do not seat at all. In such instances rapid wear takes place and considerable losses in pump capacity and general efficiency result.

The main object of the present invention 35 is to generally improve and simplify pumps of this character; to reduce the number of parts employed; to insure proper alignment of the reciprocating parts and proper functioning of the valves; further to provide a 40 single unit which will serve three functions: first, that of a valve cage and guide; secondly, a pump rod and a plunger rod coupling; and third, that of a cross head or guide for the pump rods and plunger rod.

45 Another object of the invention is to provide a combination pump rod guide, coupling and valve cage, which is simple and substantial in construction and accessible for inspection, repair, etc.

50 Further objects will hereinafter appear.

The invention consists of the parts and the construction, combination and arrangement of parts as hereinafter more fully described and claimed, having reference to the 55 accompanying drawings, in which—

Fig. 1 is a central, vertical, longitudinal

section of a deep well pump showing the application of the invention.

Fig. 2 is a side elevation of the pump rod guide, coupling and valve cage.

Fig. 3 is a central, vertical, longitudinal section of the same.

Referring to the drawings in detail, and particularly to Fig. 1, A indicates the barrel or cylinder of a deep well pump, 2 the piston or plunger, 3 the plunger rod, 4 the foot valve, and 5 and 6 a pair of check valves, the function of which will hereinafter be described. That portion of the pump which embodies the subject matter of the present 70 invention is generally indicated at B and will hereinafter be termed a combination pump rod guide, coupling and valve cage. This title is rather descriptive as the member B serves three functions: first, that of a 75 pump rod and plunger rod guide, secondly, that of a valve cage and guide, and third, that of a coupling between the pump rods and the plunger rod. The member B is particularly illustrated in Figs. 2 and 3. It 80

consists of a casting, the upper end of which is internally threaded as at 7 to receive the pump rod 8. The lower end is also internally threaded as at 9 to receive a coupling 10 which serves three functions: first, that of a valve seat; secondly, that of a plunger rod coupling; and third, that of a guide for the valve. The lower end of the coupling 10 is internally threaded as at 11 to receive the plunger rod 3, and as this rod is hollow or tubular as shown, it will be seen that it may cooperate with the coupling 10 to form a guide for the valve generally indicated at 12. This valve is of the disk type and seats on the upper end of the coupling 10. Forming 95 an extension of the valve 12 is a rod 13, and secured on the lower end thereof is a guide 14. This guide forms a sliding fit with relation to the interior surface of the rod 3, and as the guide 14 is spider shaped, free flow of 100 water will be permitted.

The member B so far described therefore serves not only as a coupling for the rods 8 and 3, but it also serves as a cage for the valve 12 and as a guide therefor. It still 105 serves another function, to-wit, that of a cross head or guide for the rods 8 and 3, and as an upper guide for the valve. This is accomplished by providing four or more radiating arms 15, on the outer ends of which are formed shoes 16. These shoes engage the interior surface of the well casing C and as

such form a cross head or guide for the rods referred to, thereby maintaining proper alignment between the rods and the piston or plunger, and as the inner ends of the arms 5 terminate at a point adjacent valve 12 an upper guide is formed therefor. The general operation of the pump is as follows:

During the upward movement of the piston 2, water will enter through the foot valve 4 and fill the lower chamber of the barrel or cylinder A. During the downward movement the foot valve will close and the water will be forced upwardly through the hollow plunger rod 3. It will thus raise the valve 12 from its seat and the water will freely discharge between the radiating arms 15, directly into the interior of the well casing C by which it is conveyed to the top of the well and discharged in any suitable manner. 10 During the downward stroke of the piston or plunger 2, water will also enter the upper chamber of the barrel through ports such as indicated at 17. The valve 6 will be raised from its seat during this stroke of the plunger 15 and the water will thus pass downwardly into the upper chamber through by-pass passages indicated at 18. During the next upward stroke of the plunger, the water previously admitted will reverse its flow 20 through the passages 18 and valve 6 will close. The upper valve 5 will then be raised from its seat by the upward pressure of the water which will freely discharge into the casing. In other words valves 5 and 6 cooperate 25 with the upper chamber formed in the barrel, while the foot valve 4 and the check valve 12 carried in the upper end of the plunger rod cooperate with the lower chamber formed in the cylinder. A double acting deep well reciprocating pump is in this manner obtained and, practically speaking, a continuous flow or discharge is secured in the casing C. Perfect alignment of the reciprocating parts with relation to the casing 40 and the pump barrel carried thereby is maintained by the arms 15 and the shoes 16. A guide is formed for the upper valve 12, which insures proper seating and functioning thereof and a coupling between the rods 45 8 and 3 is simultaneously formed, thus materially reducing the number of parts employed and simultaneously insuring full pump capacity and efficiency.

By referring to Figs. 2 and 3 in particular, it will be noted that the upper portion of the casting is cone shaped as indicated at 18 and that the lower end thereof terminates in a flat disk like face 17; further, that the diameter presented by this face is considerably less than that of the valve 12. This is of considerable importance as it allows the water to strike the outer annular edge of the valve and cause comparatively rapid seating thereof during the upward stroke, thus 55 eliminating the use of springs and like mech-

anisms now commonly employed to insure seating of the valve.

Another important feature of the present invention is the provision of means for preventing hammering of the valve, particularly during the upward movement thereof. This is accomplished by forming a conical shaped recess 19 in the upper face of the valve and a complementary or cone shaped projection 20 on the lower end of the cone 70 18. The conical shaped depression or recess in the top of the valve 12 serves as a trap or water receiving pocket, and therefore cushions and stops the valve from hammering. The conical projection 20 is slightly smaller than the depression in the valve 12 and enters the said depression during the lift or upward movement of the valve. The water in the depression is thus displaced and forced between the faces formed between the lower end of the cone and the upper surface of the valve, thereby forming a cushion which positively prevents metal contact and consequent hammering. 75 80 85

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or varying uses may demand. 90 95

Having thus described my invention, 100 what I claim and desire to secure by Letters Patent is—

1. In a pump of the character described the combination with the discharge casing, a hollow pump rod and a hollow plunger rod, of a coupling member connecting the pump rod and the plunger rod and formed to prevent fluid entering the pump rod, a valve interior of said coupling, and means on the coupling forming a guide for the valve and a guide for the rods with relation to the discharge casing and permitting flow of fluid through the coupling member for passage between the casing and the pump rod. 105 110 115

2. In a pump of the character described the combination with the discharge casing, a hollow pump rod and a hollow plunger rod, of a coupling member connecting the pump rod and the plunger rod and having a wall across the lower end of the pump rod to prevent flow of fluid into the pump rod, a valve interior of said coupling, a plurality of radially disposed arms on the coupling forming a guide for the valve, and shoes on the outer ends of the arms engageable with the interior surface of the discharge casing and forming a guide for the rods, a coupling member having fluid outlet passages between said arms. 120 125 130

3. In a pump of the character described the combination with the discharge casing, a hollow pump rod and a hollow plunger rod, of a coupling member connecting the pump rod and the plunger rod and closing the lower end of the pump rod to exclude fluid therefrom, a valve head confined wholly within the said coupling, a plurality of radially disposed arms on the coupling 5 having their inner ends arranged to form a guide for the valve, shoes on the outer ends of the arms engageable with the interior surface of the discharge casing and forming a guide for the rods, a stem on the 10 valve extending downwardly into the hollow plunger rod, and a spider on the end of said stem forming a second guide for the valve.
4. A combination pump rod guide, coupling and valve cage comprising upper and lower interspaced coupling members, a plurality of radially disposed arms connecting the same, a guide shoe on the outer end of each arm, a removable coupling member carried by the lower coupling member, a valve seat formed on the upper end thereof, a disk 15 valve supported on the seat and having its upper end guided by the inner ends of the radiating arms, the pump rod being hollow and the upper coupling member having a wall closing the lower end of the hollow pump rod to exclude water therefrom, one of the coupling members having fluid outlet 20 openings therein, a tube carried by the removable coupling member, a stem on the valve projecting downwardly into said tube, and a spider on the lower end of the stem engageable with the interior surface of the tube and forming a lower guide for the 25 valve.
5. In a pump of the character described the combination with the discharge casing, the pump rod and the hollow plunger rod, of a coupling member connecting the pump rod and the plunger rod, a valve interior 30 of said coupling, means on the coupling forming a guide for the valve and a guide for the rods with relation to the discharge casing, and means for directing water 35 against the upper surface of the valve to insure seating thereof.
6. In a pump of the character described the combination with the discharge casing, the pump rod and the hollow plunger rod, of a coupling member connecting the pump rod and the plunger rod, a valve interior 40 of said coupling, means on the coupling forming a guide for the valve and a guide for the rods with relation to the discharge 45 casing, and a cone shaped stop member limiting upward movement of the valve, the cone having a diameter smaller than the upper face of the valve to direct water 50 against the said surface and to insure seating of the valve.
7. In a pump of the character described the combination with the discharge casing, the pump rod and the hollow plunger rod, of a coupling member connecting the pump rod and the plunger rod, a valve interior 55 of said coupling, means on the coupling forming a guide for the valve and a guide for the rods with relation to the discharge casing, and means for limiting the lift of the valve and for hydraulically cushioning the 60 upward movement thereof.
8. In a pump of the character described the combination with the discharge casing, the pump rod and the hollow plunger rod, of a coupling member connecting the pump rod and the plunger rod, a valve interior 65 of said coupling, means on the coupling forming a guide for the valve and a guide for the rods with relation to the discharge casing, the valve having a recess provided in its upper face and forming a water trap, the coupling having a complementary projection adapted to enter said recess during the lift of the valve and displace the water 70 contained in the recess and thereby cushion 75 the movement of the valve.
9. In a pump of the character described, the combination with the discharge casing, the hollow pump rod and the hollow plunger rod, of a coupling member including a plurality of radially disposed arms projecting from the coupling member and engaging the walls of the discharge casing 80 and having a wall disposed across the lower end of the hollow pump rod to exclude fluid 85 from the latter, a removable coupling member carried by the aforesaid coupling member and having a valve seat at its upper end disposed within the first mentioned coupling member, a disk valve supported on 90 said valve seat in alignment with and guided by the inner ends of said radiating arms, and a tube carried by the removable coupling member.
10. In a pump of the character described, the combination with the discharge casing, the hollow pump rod and the hollow plunger rod, of a coupling member including a plurality of radially disposed arms projecting from the coupling member and engaging the walls of the discharge casing 95 said coupling member having a wall arranged to close the lower end of the hollow pump rod to exclude fluid therefrom, a removable coupling member carried by the aforesaid coupling member and having a valve seat at its upper end disposed within the first mentioned coupling member, a disk valve supported on 100 said valve seat and in horizontal alignment with and guided by the inner ends of said radiating arms, a tube carried by the removable coupling member, a stem on the valve projecting 105 downwardly into said tube and a spider on the lower end of the stem engageable with 110

the interior surface of the tube and forming a lower guide for the valve.

11. In a pump of the character described, the combination with the discharge casing, 5 the pump and the hollow plunger rod, of a coupling member connecting the pump rod and the plunger rod, and having spaced radiating arms engageable with the interior surface of the discharge casing whereby to 10 effect guidance of the pump rod and the hollow rod and the coupling member, a valve disposed within said coupling member, and means operative between the valve and the coupling member to effect a hydraulic cushioning of the valve on the upward movement of the same.

12. In a pump of the character described, a discharge casing, a hollow pump rod, a hollow plunger rod, a valve cage comprising

upper and lower coupling members, the upper coupling member having a plurality of radially disposed arms, and also having a wall extending across and closing the lower end of the hollow pump rod, the lower coupling member fitting within the inner ends of the arms and supported thereby and at its inner end forming a valve seat, a valve supported on the seat and guided by the inner ends of said arms, shoes on the outer ends of the arms engageable with the interior surface of the discharge casing to guide the cage in the casing, the upper coupling member being formed to provide passage of fluid between the arms into the discharge casing, and a tube carried by the lower coupling member.

JOHN G. DORWARD.
